ELECTRIC SIGN

Filed Nov. 22, 1930

HARRY W. LAWRENCE

H. W. Lawrence

Attorney

UNITED STATES PATENT OFFICE

HARRY W. LAWRENCE, OF DENVER, COLORADO, ASSIGNOR, BY DIRECT AND MESNE ASSIGNMENTS, TO JEWELITE INC., A CORPORATION OF COLORADO

ELECTRIC SIGN

Application filed November 22, 1930. Serial No. 497,473.

This invention relates to an electric sign and has for its principal object the provision of a sign which will produce a brilliant, constantly changing, scintillating effect which 5 will be visible for a great distance in day light as well as at night.

Another object of the invention is to so construct the device that it will require but a minimum of electric current to produce 10 maximum results.

A further object of the invention is to produce a sign which will make use of the multitude of facets and angles of refraction of relatively small jewel-like lenses by illuminating them with a constantly moving light source so as to produce a resplendent glittering effect.

Other objects and advantages reside in the detail construction of the invention which is 20 designed for simplicity, economy, and efficiency. These will become more apparent from the following description.

In the following detailed description of the invention reference is had to the accompanying drawings which form a part hereof. Like numerals refer to like parts in all views 25 of the drawings and throughout the description.

In the drawings:

30 Fig. 1 is a perspective view of one adaptation of the improved sign partially broken away to show the interior construction.

Fig. 2 is a horizontal cross section therethrough taken on the line 2—2, Fig. 1.

35 Fig. 3 is a detail vertical section through the lower portion of the sign illustrating the operating mechanism.

Fig. 4 is a diagrammatic perspective view 40 illustrating an alternative form of the invention.

Fig. 5 is a detail view illustrating the preferred type of lens or jewel to be employed in the invention.

The invention comprises a light-tight sign 45 box, such as illustrated at 10. The box 10 will have a shape and size adaptable to the particular sign to be displayed and may lie in a vertical, horizontal, or other position as desired. The box 10 as illustrated is adaptable to a vertical sign.

Upon one or more faces of the box 10 the letters or characters of the sign are painted or otherwise produced as shown at 11. The outline of the letters 11 is perforated through the faces of the box 10 by means of a series 55 of holes in each of which a cut or molded glass lens or jewel 12 is positioned. The jewels 12 are preferably of the type illustrated in detail in Fig. 5, comprising a convex faceted bezel or front with a concave faceted rear and surrounded by a peripheral projecting flange 13.

The holes in the face of the box 10 are sufficiently large to just allow the convex portion of the jewel to project therethrough and 60 still retain the flange 13. The flanges of all of the jewels may be clamped in place by means of clamp plates 14 which are provided with a series of holes similar to the sides of the box 10. The plates 14 are clamped in 65 place against the jewel flanges by means of suitable clamp screws 15. The jewels, of course, could be secured in place in any other desired manner. The method of clamping the jewels in place as illustrated, is described 70 and claimed more in detail in applicant's co-pending application, Serial No. 497,523.

A rotatable lamp shaft extends longitudinally throughout the entire box 10. This shaft may be constructed in any desired manner for supporting a series of lamp bulbs 16. It is preferred, however, to construct it as illustrated, that is, with an external metal tube 17 carrying a series of lamp socket holes 18 and a second conductor tube 19 positioned 75 within the tube 17 and spaced therefrom by means of insulators 20. The base tips of the lamp bulbs 16 contact, when screwed in place, with the internal conducting tube 19 and the two tubes 17 and 19 form conductors for 80 carrying electricity to the lamps.

A series of socket holes 18 may be provided so that the number and position of the lamps 16 may be varied to obtain the best results upon the particular sign characters being used.

The external tube 17 terminates in a collector ring 21 to which current is conducted through a brush 22. The internal conductor tube 19 terminates in a collector ring 23 to 100

which current is conducted by means of a second brush 24. The tube 17 is supported within the box 10 upon suitable insulated bearings 25. The internal tube 19 is connected through suitable insulation with a speed reducer 26 which in turn is operably connected with an electric motor 27. The motor, drive mechanism, and collector rings can be conveniently housed in a compartment 38 at one extremity of the sign.

It can be seen from the above description that the motor 27 will constantly rotate the lamp shaft and the series of lamps carried in the socket opening 18 causing the lamps to project their beams through the jewels 12 at an infinite number of constantly changing angles.

This causes a constant change in the angle of illumination of the various facets of the jewels 12 resulting in an animated, scintillating, glittering effect that has been found to have great visibility in daylight as well as at night.

It has been found desirable, but not necessary, to also illuminate the jewels by means of stationary reflected light. This is preferably accomplished by means of a series of stationary lamps 28. These lamps 28 can be supported from any desired sockets or conductors. It is preferred, however, to use a special lamp border 29 which, together with the lamp shaft construction, is illustrated, described and claimed more in detail in applicant's co-pending application, Serial No. 35 497,524.

It has been found that a much better effect can be obtained from the jewels 12 if the direct light rays from the stationary lamps 28 are prevented from striking them. This is accomplished in the present invention by placing the lamps 28 upon the same face that carries the jewels 12 and providing baffle plates 30 between the jewels and the lamps.

In large signs there might be a great waste 45 of illumination in the blank spaces between the letters and characters. This waste can be reduced by blocking off the blank spaces by means of partitions as shown at 37, Fig. 1.

As can be readily seen one of the principal 50 features of this invention is the idea of constantly moving a light source to different positions in the rear of a series of faceted lenses or jewels. This can be accomplished in many 55 ways, the rotating shaft of Figs. 1, 2, and 3 is one illustration of the principle. Another form is shown in Fig. 4, in which the sign character is indicated at 31 studded with jewels 32. In the rear of the jewels 32 is a 60 revolving disc 33 mounted upon a rotating shaft 36 and carrying a series of electric lamps 34. As the series of lamps 34 rotates it will throw the light beams upon the facets of the jewels 32 and constantly differing angles 65 and create the same scintillating effect as

previously described. This form of the invention could be used in place of the rotating lamp shaft of Fig. 1, when desired.

In the latter form of the invention the bases of the lamps 34 would be screwed into the plate 33 and the tips of the lamp bases would contact with a second contact disc 35 which would complete the electric circuit to the lamps, thereby eliminating the necessity for separate sockets and wiring.

In the sign illustrated the sign characters are outlined on an opaque sign face by means of the lenses 12. It is desired to be understood that the reverse of this procedure is also contemplated, that is, the entire area of the sign face covered with lenses with the characters either opaque or outlined in different colored lenses.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. An electric sign comprising: a sign box; sign characters carried by said sign box, there being perforations through said box outlining said characters; faceted lenses carried in said perforations; a longitudinal shaft extending through said box behind said characters; a series of electric lamps projecting from said shaft; means for rotating said shaft, said shaft comprising: an inner contact bar; an outer lamp supporting bar surrounding, spaced and insulated from said inner bar, there being perforations in said outer bar so as to allow a lamp base to project therethrough into contact with said inner bar to close a circuit therewith; a collector ring in circuit with said outer bar; a second collector ring in circuit with said inner bar; brushes contacting with said collector rings so as to conduct current to said bars to illuminate said lamps.

2. A rotatable light supporting shaft for electric signs comprising: an inner contact bar; an outer lamp supporting bar spaced and insulated from said inner bar, there being perforations in said outer bar so as to allow lamp bases to project therethrough into contact with said inner bar to close a circuit therewith; and means for rotatably supporting said two bars as a unit.

3. A rotatable light supporting shaft for electric signs comprising: an inner contact bar; an outer lamp supporting bar spaced and insulated from said inner bar, there being perforations in said outer bar so as to allow lamp bases to project therethrough into contact with said inner bar to close a circuit therewith; means for rotatably supporting said two bars as a unit; a collector ring in

circuit with said outer bar; a second collector ring in circuit with said inner bar; and brushes contacting with said collector rings so as to conduct current to said bars to 5 illuminate said lamps.

4. A rotatable lamp supporting shaft for electric signs comprising: an inner bar; an outer bar; insulated spacing means arranged to space said outer bar uniformly about said 10 inner bar, there being perforations in said outer bar to allow a lamp base to project therethrough into contact with said inner bar; a bearing member for supporting said shaft; and an insulated spacing member supporting 15 said bearing member from said outer bar.

5. An electric sign comprising: a sign box; sign characters carried by said sign box, there being perforations through said box outlining said characters; faceted lenses carried in 20 said perforations; a motor compartment formed in said sign box; a partition separating said motor compartment from said sign box; a longitudinal shaft extending through said box behind said characters; a 25 bearing for supporting said shaft on said partition; a series of electric lamps projecting from said shaft; means in said motor compartment for rotating said shaft; and means for supplying current to the lamps on 30 said shaft.

In testimony whereof, I affix my signature.
HARRY W. LAWRENCE.
